No. 723,639.

PATENTED MAR. 24, 1903.

D. J. BLISS.

WATER FILTER.

APPLICATION FILED JUNE 9, 1902.

NO MODEL,

THE NORRIS PETERS CO., PHOTO-LITHO., WASHINGTON, D. C.

UNITED STATES PATENT OFFICE.

DWIGHT J. BLISS, OF CARTHAGE, MISSOURI.

WATER-FILTER.

SPECIFICATION forming part of Letters Patent No. 723,639, dated March 24, 1903.

Application filed June 9, 1902. Serial No. 110,871. (No model.)

To all whom it may concern:

Be it known that I, DWIGHT J. BLISS, a citizen of the United States, residing at Carthage, in the county of Jasper and State of Missouri, 5 have invented certain new and useful Improvements in Water-Filters; and I do declare the following to be a full, clear, and exact description of the invention, such as will enable others skilled in the art to which it applies to make and use the same.

The invention relates to improvements in water-filters.

The object of the invention is to provide a water-filter of the gravity type which shall be simple of construction, durable in use, comparatively inexpensive of production, efficient in action, and also to provide means for thoroughly and effectively cleaning the surfaces of the filtering-cylinder.

With the above and other objects in view, which will readily appear as the nature of the invention is better understood, said invention consists in certain novel features of construction and combination and arrangement 25 of parts, which will be hereinafter fully described, defined in the appended claims, and illustrated in the accompanying drawings, in which—

Figure 1 is a longitudinal vertical sectional view through my improved filter, illustrating the cleaner in operative position therewith. Fig. 2 is a horizontal sectional view on the line $x-x$ of Fig. 1, the cleaner being removed. Fig. 3 is a side elevation of the cleaner. Fig. 35 4 is a cross-section on the line $y-y$ of Fig. 3. Fig. 5 is a cross-sectional view of a modified form of cleaner. Fig. 6 is a view of another form of cleaner. Fig. 7 is a view of still another form of cleaner.

In the drawings, 1 denotes the filter-casing, which may be of any suitable shape and capacity and which is shown in the present instance as consisting of a bucket provided with a bail 2, by means of which it may be supported from above.

3 denotes the filtering-cylinder, which consists of a porous body having filtering-ducts 4, extending from its lower end upwardly and ending short of the upper end of the cylinder and arranged in annular order and provided with a through-bore 5. This cylinder is seated upon a rubber gasket 6, located in

the bottom of the filter-casing, said gasket surrounding the lower ends of the filtering-ducts 4 and forming a chamber 7. This gasket forms a water-tight joint between the lower end of the cylinder and the casing and prevents water from entering the chamber 7 between the lower end of the cylinder and bottom of the casing. If desired, I may also place a cement packing 8 between the lower end of the cylinder and bottom of the casing and surrounding the rubber gasket 6.

9 denotes a tube or sleeve which extends through the central bore 5 with both ends 65 and has its lower end projecting through the bottom of the casing, and if the casing is designed to be supported upon a base 10 the lower end of said sleeve also projects through this base. Each end of the sleeve is screw-threaded, as shown in Fig. 1, and upon each screw-threaded end is engaged a clamping-nut 11, the upper one of which has confined between it and the filtering-cylinder a spring-washer 12.

The sleeve at that portion in its length which is located above the bottom of the casing and lower end of the cylinder is provided with discharge-openings 13, which communicate with the chamber 7 and lead the water 80 from said chamber into the sleeve, from which it discharges through a nipple 14, secured in the lower end of said sleeve out through a pipe 15, connected to the lower end of said nipple.

The water to be filtered is placed in the casing and percolates through the porous cylinder into the ducts 4 and from these ducts discharges into the chamber 7 and is led off therefrom in the manner just specified. The 90 exterior surfaces of cylinders of this character will in time become coated with foreign matter caught by the cylinder in the percolation of the water therethrough, and to remove this foreign matter or sediment I have provided a novel form of cleaner which may be readily attached to the cylinder and by means of which the exterior surfaces thereof may be thoroughly and expeditiously cleaned.

The cleaner comprises an abrasive body 16, 100 preferably of a length corresponding to the length of the cylinder and secured in any suitable manner to a metal frame 17, preferably of channel-iron having a cross-sectional

construction, as illustrated in Fig. 4. An operating-bar 18 is pivoted by a bolt 19 to the frame 17 and has its upper end projecting upwardly within convenient reach to be 5 grasped by the hand of the operator. A pivotal post 20 is connected to the bar 18 by a link 21, and said post is adapted to fit within the upper end of the sleeve 9. The link 21 has a horizontal row of apertures 22, through one 10 of which extends a bolt 23, whereby as the filter-cylinder or abrasive body wears said body may be adjusted to the cylinder to compensate for said wear without changing the vertical position of the bar 18 with respect to 15 the casing, and said bar will always be in a position to be freely revolved within the casing. 24 denotes a plug arranged within said sleeve near its lower end and is designed to prevent the escape of water from the pail 20 through the sleeve when the pivotal post 20 is removed, and in Figs. 5, 6, and 7 I have shown modified forms of frames for securing 25 the abrasive body, Figs. 5 and 6 showing an angle-iron frame and Fig. 7 showing a frame consisting of two bars between which the abrasive body and the bar 18 are clamped. Any other suitable form of frame may be provided without departing from the spirit of the invention.

30 The filtering-cylinder 3 may have on its lower end a series of radiating grooves or channels 3^a, affording communication between the central bore 5 and the filtering-ducts 4, so that should the lower ends of any of the 35 ducts 4 be accidentally covered by the slipping of the rubber gasket or from other causes there still will be an outlet from such duct for the filtered water.

In operation when it is desired to clean the 40 sides of the cylinder the frame is inserted in the casing between the walls of the filter and the interior wall of the casing, with the post 20 in the sleeve 9. The upper end of the bar 18 is grasped and the abrasive body is caused 45 to rotate about the cylinder, and by applying outward pressure against the handle in the act of swinging it around the cylinder the pressure against the sides of the cylinder may be varied as the case may require, it being 50 observed that the bar 18 has a pivotal connection with the link as well as with the frame carrying the abrasive body; and this permits of a varying pressure being applied as the abrasive body is revolved around the cylinder.

55 From the foregoing description, taken in

connection with the accompanying drawings, it is thought that the construction, mode of operation, and advantages of my improved water-filter will be readily apparent without requiring a more extended explanation. 60

Various changes in the form, proportion, and the minor details of construction may be resorted to without departing from the principle or sacrificing any of the advantages of this invention. 65

Having thus described my invention, what I claim as new, and desire to secure by Letters Patent, is—

1. The combination with a filter-casing and a filtering-cylinder arranged therein; of a bar 70 of abrasive material extending substantially the full length of the filtering-cylinder, an operating-bar pivotally connected to the bar of abrasive material and pivotally and rotatably connected to the filtering-cylinder, substantially as described. 75

2. The combination with a filter-case and a filtering-cylinder arranged therein; of a bar 80 of abrasive material extending substantially the full length of the filtering-cylinder, an operating-bar pivoted to the abrasive bar, a pivotal post connected to the cylinder, and a link connecting the pivotal post to the operating-bar, substantially as specified. 85

3. The combination with a filter-case and a 85 filtering-cylinder arranged therein; of a bar of abrasive material extending substantially the full length of the filtering-cylinder, an operating-bar pivoted to the abrasive bar, a pivotal post connected to the cylinder, and a link 90 adjustably connecting the pivotal post to the operating-bar, substantially as set forth. 95

4. The combination with a filtering-case and a filtering-cylinder having a central bore, a post located within said bore, a bar of abrasive material extending substantially the full length of the filtering-cylinder, an operating-bar connected to the abrasive bar, a link one 100 end of which is pivotally and adjustably connected to the operating-bar and the opposite end of which is fixed to said pivotal post, substantially as and for the purpose set forth. 105

In testimony whereof I have hereunto set my hand in presence of two subscribing witnesses.

DWIGHT J. BLISS.
